UNITED STATES PATENT OFFICE.

JOHN MARTIN RAY, OF AMARILLO, TEXAS.

PROPELLER.

Application filed November 14, 1921. Serial No. 515,178.

To all whom it may concern:

Be it known that I, JOHN MARTIN RAY, a citizen of the United States, and a resident of Amarillo, in the county of Potter and State of Texas, have invented certain new and useful Improvements in Propellers, of which the following is a description, reference being had to the accompanying drawings, which form a part of my specification.

10 My invention relates to propellers for use on aeroplanes, submarines and the like and has for its object the provision of a construction wherein the blades are caused to oscillate while revolving or traveling through an orbit concentric with the power-imparting shaft or member.

The purpose of my invention is to provide a propeller wherein the axes of the blades are disposed in alignment, with the blades 20 arranged diametrically of the power imparting shaft or member which constitutes the common axis about which the blades revolve and each blade normally arranged at the desired angularity relative to its horizontal 25 axis, in conjunction with means whereby the mountings connected with the inner ends of the respective blades are provided with a secondary axis, aligned with the axis through the blades, about which said mountings may be tilted or oscillated in directions 30 lengthwise of the major axis or propeller-shaft, so that the blade which is moving downwardly or through the power imparting portion of its orbit will be disposed at the proper angle relative to the air or water 35 so as to provide a forward lifting action or a rearward pulling action as the case may be, while the opposite blade, that is to say, the blade which is moving upwardly through 40 the non-effective part of its orbit will have been oscillated or rotated about its own axis into a position where the flat faces of the blade will be disposed vertically so that the flat faces of said blade will offer substantially 45 no resistance in the rotation to the air or water; the construction being such that each blade will oscillate into and out of power-imparting position at the initial and terminating portion of its downward travel during 50 each revolution of the propeller.

Another object of my invention is to provide means, operable from the seat of the operator whereby the direction of the inclination of the flat surface or face of each 55 blade in its downward or operative portion

of revolution may be quickly altered or determined during the revolution of the propeller.

The objects and advantages of my invention will be more readily comprehended 60 from the detailed description of the accompanying drawings, wherein:—

Figure 1 is a longitudinal sectional view of my improved propeller with a portion of the operating shaft and shifting mechanism 65 broken away; the view being taken substantially at right angles to the axes of the blades.

Figure 2 is a vertical sectional view taken on the line 2—2 of Figure 1 looking in the 70 direction of the arrows.

Figure 3 is a partial phantom view, in perspective of the blades—partly broken away, with the blades in normal position.

Figure 4 is a schematic view in partial 75 side elevation with the blades or propeller in normal position.

Figure 5 is a similar view with the propeller adjusted for forward and upward 80 pulling action.

Figure 6 illustrates the propeller adjusted whereby resistance is shifted to the opposite side and resistance reversed.

The particular exemplification of the invention as illustrated in the drawings comprises a power shaft 10 adapted to be driven by any suitable motive power, with the outer end disposed through a sleeve 11 which may be supported by any suitable bracket or standard as at 12 and held against rotation; 85 that is to say the power shaft 10 is free to rotate in the non-rotating sleeve 11. The sleeve 11 at suitable points is shown reduced or shouldered to receive socketed or grooved rings 13 which constitute raceways for the 90 anti-friction or ball bearings shown at 14 whereby a suitable shell or casing 15 is rotatably mounted on the end of the sleeve. The casing is preferably constructed in two parts 15 and 15^a as shown in Figure 1, with the parts removably bolted together in any suitable manner as for example by bolts 16; the part 15 being rotatably mounted by means of the anti-friction bearings described, while the part 15^a is provided with 95 a small hub portion in which suitable anti-friction and thrust bearings 17 are mounted in conjunction with a bushing 18, as shown in Figure 1.

The outer end of the shaft 10 is shown 110

threaded to receive a suitable nut and plate, indicated at 19, whereby the casing is maintained in place and caused to rotate with the shaft 10 by reason of suitable connections 5 between the plate and the casing as for example bolts or screws 20; the nut in turn being held against accidental removal in any suitable manner. The casing members or shells 15 and 15^a at diametrically opposite 10 points are provided with inwardly disposed apertured bosses as at 21, 21, see Figure 2; said bosses being preferably disposed at the juncture of the two members or shells 15, 15^a to permit the easy insertion of the reduced inner ends or portions 22 of the propeller blades 23 and 24. The blade proper is provided with a comparatively flat surface and twist or angularity of substantially twenty degrees to its axis, intermediate of 15 its ends; with the twist or angularity of the blades being in opposite directions to each other as shown in Figure 4. The inner end 22 of each blade is free to rotate or turn in the bosses 21 of the composite casing 15, 15^a, 20 and said inner ends 22 are secured to or may be made integral with an annular member or ring 25 which latter, at diametrically opposite points intermediate of the points of connection of the blades therewith, is shown 25 provided with tapped openings or apertures 26, 26,—that is to say at points 90 degrees removed from the point of connection of the blades to the ring 25,—to receive trunnions or members 27, 27 whose inner non-threaded 30 ends are disposed in sockets or openings formed in an annular member or ring 28 arranged concentric with the annular member or ring 25. The inner circumference of the annular member or ring 28 is shown provided with a circumferential groove adapted 35 to receive an annular member or ring 29 provided with a hub portion 30 whose internal diameter is considerably greater than the external diameter of the non-rotating 40 sleeve 11; the relation between annular members 28 and 29 being such that member 28 may be free to rotate about member 29; the free running rotation being assisted, if desired, by means of anti-friction ball bearings 45 as at 31 disposed in suitable grooves formed in the groove of member 28 and the sides of member 29; the bearings on the opposite side of member 29 being maintained in place in any suitable manner, as for example by means of a flat ring 32 which may 50 screw into a threaded socket in the side of member 28 and said flat ring 32 in turn may be held in place by means of the washer or nut 33, see Figure 1. The annular member 55 29 is trunnioned or journalled to the sleeve 11 by means of the pins or bolts 34, 34 extending through apertures in annular member 29 and threaded in the tapped bosses or enlargements 35 formed at diametrically opposite points on sleeve 11. The trunnions 60 or pivot connections of annular member 29 with sleeve 11 are disposed at right angles to the trunnions or pivotal points 27 of annular member 25 on annular member 28, that is to say the pivotal points 34 of annular member 29 on sleeve 11 are disposed 90 degrees from and intermediate of the pivotal points 27 whereby annular member 25 is secured to annular member 28, and therefore are disposed in axial alignment with the blades 23, 24, see Figure 2.

The sleeve 11, as well as the bushing or bearing members of the housing section 15^a on the sleeve, are longitudinally slotted to receive the key or slide-rod 36 which is 60 adapted to extend to a suitable point within the housing from the operating mechanism or lever (not shown) disposed within reach of the operator, and said key or member 36 is adapted to be moved lengthwise of sleeve 11 for the purpose hereinafter described. The sleeve 11, at suitable points, may be provided with supporting members or rings as at 37 whereby proper positioning of the slide-rod 36 will be maintained. The slide-rod 36, at 65 a point adjacent its inner end, is shown provided with an upwardly disposed protrusion preferably in the form of a spherical member 38, which is adapted to extend into a socket 39 formed on the interior of annular member 29. The projection or extension 38 of the slide-rod 36 will cause the annular member 29 to be tilted about its pivotal points or pins 34, 34, through the arc of a circle that is in a direction lengthwise of the 70 operating shaft 10 and sleeve 11, namely into the positions indicated in Figures 5 and 6. In view of the fact that the annular member 28 with the ring 32 provides an internal groove to receive member 29, it is apparent that the annular member 28 must also tilt with the member 29 into the same position and by reason of the connection of annular member or ring 25, through the medium of trunnions 27, 27 with members 28, it 75 is evident that the annular member 25 likewise will tilt into the same position as the annular member 29, thus causing the blades to be turned or tilted, relative to their axes. As the composite housing or shell 15, 15^a is 80 rotated through the medium of power shaft 10, it is apparent that the propellers 23, 24 will be rotated about the longitudinal axis of power shaft 10, that is to say the blades will rotate with the shaft. As the inner ends 22 of the blades are secured to the annular member or ring 25, the blades 23 and 24 will be twisted or moved about their own axes to an extent equivalent to the degree of oscillation given to annular member 85 29 and therefore to members 28 and 25, with the result that as the housing and blades, together with members 28 and 25, are rotated about the non-rotating sleeve 11 and member 29, the angle of incidence of the blades 90

will be altered and each blade caused to assume two positions in each revolution with the shaft; that is to say, the blade which is moving downwardly through its orbit will be at the proper or desired angularity relative to its own axis so as to offer proper resistance or rather provide a forward or rearward pulling force, while the blade moving upwardly in each revolution will have been oscillated to a position where it is disposed substantially vertically so as to offer practically no resistance to the elements (air or water as the case may be). Each blade therefore is caused to assume a power-imparting and a non-power imparting position during each revolution; the blade moving from a power-imparting position as it approaches the lowermost point in its orbit and assuming a power-imparting position as it reaches and passes about the uppermost point in its orbit. The blades are set at a predetermined angle to each other and to their axes when the mechanism is in normal position and the angularity of the blades to the housing may then be altered so as to have the blades at the desired angle of incidence whereby to provide a forward upward pulling action or a forward downward pulling action when the annular members, through proper movement of the slide-rod 36, are tilted toward either one of the positions indicated in Figures 5 and 6; the angle of incidence of each blade in the operating stroke of its revolution therefore being under the control of the operator; with the oscillation of the blades being possible while the propeller is in operation.

With the propeller in its normal position as shown in the first four figures, where both blades are twisted or given opposite angularity and so secured to the ring 25, both blades will provide the same effect and offer equal resistance, thereby providing a direct pull. By shifting the slide-rod 36 toward the outer end of the sleeve 11, the blade carrying ring 25, (as well as members 28 and 29) will be tilted into the position shown in Figure 6, thereby moving the blades, for example through substantially twenty-five degrees, relative to their axes and therefore also from their normal positions, so that the one blade will be disposed substantially at an angle of forty-five degrees to its axis during a portion of its revolution, to-wit the blade 23, while the blade 24 will be disposed substantially perpendicular during a portion of its revolution, as shown in Figure 6; it being understood, that each blade is made to assume the two positions, relative to their respective axes, during each complete revolution of the propeller shaft and housing. With the blades positioned as described and shown in Figure 6 it will be apparent that blade 23 offers the resistance and therefore is the operating blade, while

blade 24 is made to split the air or water, offering little or no resistance; these conditions changing as the respective blades approach the opposite sides of the shaft in their rotation.

If reverse action on the part of the propeller is desired, the operator shifts slide-rod 36 toward the left in Figures 1 and 4, causing ring 25, with members 28 and 29 to be tilted into the position indicated in Figure 5. Positioning of the composite blade holding mechanism as described, will cause blade 24 to assume an angle of substantially forty-five degrees during the operative part of its rotation, while blade 23 will be disposed substantially perpendicular as shown in Figure 5; it being understood that each blade will assume the position of the other as it arrives on the opposite side of the shaft from that occupied by it in Figure 5. It will also be noted that shifting of the mechanism from the position shown in Figure 6 to that shown in Figure 5, will change the air resistance from one side to the other and therefore reversing resistance from the near side in Figure 6 to the far side in Figure 5.

The blades are off-set from center of axis so as to balance the composite blade-ring while rotating; the blades being twisted so as to have a screwing action and being disposed substantially in the same manner at the inner or hub ends thereof as at the points or outer ends, thus providing resistance from hub to tip. The blades are off-set to one side of the center line or axes thereof, rearward to the direction of rotation of the blades, so as to balance the blades and the blade ring. The blades are also bent or bowed slightly in a direction toward the shaft, for the purpose of creating either downward or upward air pressure on the face or forward side of the blades relative to the direction of rotation, in order to create resistance against air pressure, thus tending to provide a lifting or pulling effect on the shaft housing while in rotation; the blades being thrown off balance or off center in the opposite direction to the direction of air pressure.

I have referred to my improved propeller as being especially adapted for aeroplanes, submarines and other vessels, but it will be understood that it is equally adapted for use on wind-mills or for hydraulic power generating purposes, and while I have shown what I believe to be the simplest and best embodiment of my invention, which has been described in terms employed merely as terms of description and not as terms of limitation, structural modifications are possible and may be made without, however, departing from the spirit of my invention.

What I claim is:

1. A propeller, comprising a power shaft, 130

- a non-rotating sleeve disposed about the shaft, a housing disposed about the ends of the shaft and sleeve and secured to the shaft so as to rotate therewith, propeller blades 5
 5 journaled in said housing at diametrically opposite points, non-rotating means oscillatably secured to said sleeve within the housing, means rotatable on said first means and oscillatable therewith, a portion of said 10 last means having the inner ends of the blades immovably secured thereto, and means whereby the non-rotating means with the second mentioned means may be tilted in a direction lengthwise of the shaft, 15 whereby each propeller blade is caused to partially rotate about its own axis during each revolution of the power shaft.
2. A propeller, comprising a power shaft, a housing secured to the end of the shaft and rotatable therewith, propeller-blades carried by said housing so as to rotate with said shaft, the blades being free in the housing to move about their own axes, non-rotating means concentric with said shaft and 20 disposed within the housing, a portion of said means being tiltably mounted at points in axial alignment with the axes of the blades, and means intermediate of the tiltably mounted portion of the non-rotating 25 means and the inner ends of the blades consisting of a portion rotatable on the tiltable portion of said non-rotating means and a second portion pivotally secured to the first portion and secured to the inner ends of the 30 blades, whereby the angle of incidence of each blade may be altered in its revolution with the housing and power-shaft.
3. A propeller of the character described, comprising a power-shaft, a housing rotatable with said shaft, propeller blades journaled in said housing and adapted to rotate therewith, a non-rotating sleeve disposed about said shaft, an annular member concentric with and tiltably mounted on said sleeve 40 at points in axial alignment with the blades, a second annular member rotatable about said first member, a third annular member pivotally secured to the second member at points at right angles to the pivotal points 45 of the first member, said third member being connected to the inner ends of said blades, and a slide rod operatively connected with the first annular member whereby the latter may be tilted and the angle of in- 50 cidence of the blades altered during their revolution with said housing.
4. A propeller of the character described, comprising a propeller shaft, a non-rotating member concentric with said shaft, an annular non-rotating member tiltably secured to the first member, a third member provided with an annular groove to receive the second member and being free to rotate thereon, a ring disposed about the third member and pivotally secured thereto, blades secured at 60 their inner ends to said ring to rotate therewith, said blades being offset toward one side of the center line thereof, rearward to the direction of their rotation when the blades are in normal position and the ring 65 is at a point intermediate of its extreme points of oscillation, while the outer ends of said blades are dipped in a direction toward the propeller shaft.
5. A propeller, comprising a rotatable 70 shaft, a housing disposed about the shaft and secured thereto so as to rotate therewith, blades carried by the housing, an annular member within said housing to which the inner ends of the blades are rigidly secured, a non-rotating member within the housing, a non-rotating annular member tiltably secured to the second mentioned member, an internally grooved annular member rotatable about the third mentioned member, disposed within and having pivotal connection with the first mentioned member, the blades being offset from their axes in such direction 75 that the air pressure thereon effects pressure on said third mentioned member,—when the latter has been tilted into either of its extreme positions,—through the first and fourth mentioned members,—while the latter are passing through the declining portion of their rotation about said third mentioned member,—which tends to rotate the shaft, through the housing, in the direction of rotation of the shaft, and a control rod disposed lengthwise of the shaft and having ball-and-socket connection with the third 80 mentioned member, whereby the latter may be tilted about its pivotal points on the second mentioned member.

JOHN MARTIN RAY.
